UNITED STATES PATENT OFFICE.

JOHN ALFRED GRIER, OF SUMTER, SOUTH CAROLINA.

REFRIGERATING MACHINE.

Application filed January 25, 1924. Serial No. 688,539.

This invention relates to improvements in refrigerating machines and has for its primary object the production of a machine in which a relatively large volume of refrigerating medium may be circulated under a relatively low pressure; whereby a simple, fairly compact and highly efficient apparatus may be produced which is especially adapted for domestic use and in butcher shops, florists, groceries, soda fountains and a wide range of industrial uses. Other objects of the invention are: (1) To provide a lubricating and a separator system whereby the moving parts are thoroughly lubricated and the separator removes all of the lubricant from the compressed gases before they pass on into the condenser and become chilled by the condensing water. This method keeps any lubricant from getting into the condenser and insulating the tubes by coating them. (2) To make a machine which is fairly compact, yet has every part instantly accessible, so that in case of trouble, no other parts would have to be torn down to get to the part that needs attention. (3) To provide a machine which is entirely devoid of valves having stuffing boxes, thus reducing chances for leakage; and having no valves to operate, this apparatus can be operated by persons of no technical knowledge whatever. Further objects will sufficiently appear from the detailed description hereinafter.

To these and other ends the invention consists in certain improvements and combinations including the following: The main principle of my refrigerating machine or system is that of circulating a refrigerant which on the high side is liquid or largely liquid, and on the low side becomes vapor. My refrigerant may be any one of a number of well known substances commonly employed for this purpose, for example ethyl chloride. In order to circulate a large volume of the refrigerant under relatively low pressure, I have adopted a certain novel grouping and arrangement of the apparatus, and have specially designed some of the pieces of apparatus, so that the refrigerant as it comes into the compressor is fed down through a reservoir and up through a separator, thence to the condenser and by suitable piping back to the evaporating coils or grids. A rotary compressor is employed, driven by any suitable motor, preferably a

rotary motor, and specifically described herein as an electric motor. The compressed gases pass down through a large exhaust opening in the bottom of the compressor into a lubricant chamber from which they pass upward through a specially constructed separator, which takes out all the oil and throws it down into the lubricant chamber. The gases under pressure pass from the separator into the condenser, while the pressure maintained on the lubricant forces it up in constant circulation through the bearings and working parts of the compressor. The machine is made compact by having the motor, compressor, separator, condenser, and charging valve, all mounted on the same base, but as separate units, so that any one is accessible without disturbing the others. The base, moreover, contains the lubricant chamber or reservoir, and forms a part of the working circuit of the refrigerant. The machine is rendered devoid of valves by using a rotary compressor, and connecting the same up in the circuit with fixed pipe connections throughout so that liability to leakage is reduced to practically zero, the only point requiring special attention being the stuffing box of the compressor, which is designed to withstand the highest pressures likely to occur.

As a part of my invention, which I shall claim as novel herein, I construct my separator as a column with communicating up and down spiral paths for the refrigerant, the lower end of the column draining into the lubricant chamber, so that centrifugal force, as well as the force of gravity, will operate to separate out the lubricant from the refrigerant as the latter passes up and down through the spirals, and up again through the length of the column.

My invention is illustrated in the accompanying drawings, in which like parts are indicated by the same numerals.

Figure 1 is an end elevation of the preferred type of my machine.

Figure 2 is a front elevation.

Figure 3 is a plan showing relation and location of the parts.

Figure 4 is a section of compressor base showing separator in section and compressor partly in section, taken on the line A, A, of Figure 2.

Referring to the drawings: 1 is an electric motor, 2 is a rotary compressor, 3 is the

lubricant separator, 4 is a base for the compressor and the separator which forms a reservoir for the lubricant. The combination 2, 3 and 4 is very novel and will be 5 more fully described hereinafter. 5 is the condenser which stands vertical in this case although I may mount it horizontally or otherwise, as may best suit the circumstances of particular cases. The separator and condenser are connected by the pipe or conduit 15. The charging valve 19 is connected to the condenser by the pipe 18. The pipe 21 leads the liquid refrigerant to the expansion valve 31. The expansion valve is connected 15 to the evaporating coils or grids 33 and 34 by the pipe 32. The said grids or coils interconnected by the pipe 37, are placed in a tank 35 of brine 36, and are connected to the intake side of the rotary compressor by 20 the pipe 38.

The pipe 12 leads water into the condenser. The pipe 13 leads the water from the condenser into the stuffing box end 17 of the compressor 2 where it passes through covered 25 openings in 2, to the head 16 then out through the pipe 14.

The base 4 which forms a lubricant reservoir has circular openings 40 and 41 over which are mounted the compressor 2 and the 30 lubricant separator 3 respectively (see Fig. 4). The quantity of lubricant 28 in the system is so regulated that there will always be a space between its surface and the upper wall of the reservoir 4 for the gases to pass 35 from the compressor 2 to the separator 3. The gases pass through pipe 38 into the intake 8 of the compressor 2 and after being compressed, they are discharged through the opening 40 into the lubricant reservoir 4 where they go along above the surface of the 40 lubricant and into the separator through the opening 41. The separator may consist of one or more spirals or a plurality of baffle plates but in the preferred type of my machine I use two spirals as shown. The tube 23 has a spiral 22 around its outside of such diameter as to fit tightly inside the cylinder which forms the body part of 3. The lower 45 end of the said tube 23 projects below the surface of the lubricant 28 in the reservoir, just clearing the bottom of the inside of the base 4. The lubricant keeps this end of the tube closed so that the gases have to pass around the spiral to get out, and the deeper 50 this tube projects into the liquid, the lower the liquid level may become before the seal is broken. The compressor gases pass up the spiral 22 which gives them a rapid rotary motion. The particles of lubricant 55 which may have become mixed with the gases, in the compressor, are thrown out by centrifugal force against the inner wall of the tube 3 and drain back down to the other lubricant in the reservoir below. The said 60 gases on arriving at the top have no other 65

outlet than around the spiral 25. The passage around this spiral 25 takes out all remaining lubricants, and thus cleansed the gases arriving at the bottom of the spiral 25 again turn upward through the tube 24 and pass out the opening 26 through the pipe or conduit 15 into the condenser 5. The inner spiral 25 is wound around the tube 24. This tube 24 has its upper end fitted tightly into the head 7 of the separator 3 and its lower end at a sufficient distance above the surface of the lubricant 28 so that a surge would not force the body of the lubricant up said tube. The supply of lubricant is replenished by removing the plug 30, placing a funnel in the hole and pouring in lubricant.

My condenser 5 has copper tubes (not shown in the drawing,) through which the cooling water passes, the gases filling the cylinder and surrounding the outside of the tubes. In mounting the condenser vertically my liquid refrigerant accumulates to some considerable depth, whereas if mounted horizontally it would run the whole length of the condenser and not be so deep. However, I may mount the condenser either way, without departing from the invention, the vertical arrangement being at present deemed preferable.

The liquid refrigerant passes out the bottom of the condenser 5 through the pipe 18, on through valve 19 which has been turned or placed in the running position so as to connect pipe 18 with pipe 21 and so on into the expansion valve 31. The expanded refrigerant passes through the pipe 32 into the expansion or evaporating coils or grids 33 and 34 where they absorb heat from the brine 36 and pass on back through the pipe 38 to the compressor and so on, the same cycle being repeated.

There is constant pressure on the lubricant reservoir, the separator and the condenser, known as the high side, indicated by the gauge 6, and I take advantage of this to insure efficient lubrication of the moving parts. Referring again to Fig. 4, the pressure on the surface of the lubricant 28 in the reservoir forces lubricant constantly up the feeder pipe 29, whence it goes through ducts, not shown, to lubricate all moving parts of the compressor.

The pressure on the low side of the system is below atmospheric and is indicated by the vacuum gauge 39.

The motor 1 drives the compressor 2 directly through a flexible coupling 10. The stuffing box 11 is the only opening between inside and outside of the system and it is effectively sealed against leakage by the lubricant and by a special packing.

The charging valve 19 is a three way valve with the stem normally, or when the system is operating, sealed above and below so as to

prevent its being moved. In starting operation, I connect a drum of liquid refrigerant to the charging valve at 20, and turn the valve so that the liquid feeds in at 20 and 5 on through the pipe 21 to the expansion valve 31, shutting off or dead ending the pipe 18. I then start the machine running, and let the refrigerant expand through the expansion valve into the cooling coils or grids 10 33 and 34, pass on through pipe 38 to compressor 2, through separator 3, and into condenser 5 to be again liquified. The condensed liquid accumulates in the bottom of 15 the condenser. When the required number of pounds of refrigerant have been put into the machine I turn the valve 19 so that the liquid accumulated in condenser 5 feeds through pipe 18 into pipe 21, shutting off or dead ending the pipe 20 so that the tank 20 of refrigerant can be shut off and disconnected. I then seal up the hole, where pipe 20 is connected, with a plug, and replace the top 42 of the valve 19 so as to seal it up and prevent tampering. The system is then 25 ready for continuous operation as long as the motor 1 is running.

What I claim and desire to secure by Letters Patent of the United States is:

1. In a refrigerating machine, a compressor, a motor therefor, a lubricant separator and a condenser, a base for said elements with means for securing the same thereto, a pipe circuit connecting said elements, and also connecting the compressor and condenser with the two sides of an evaporating or heat absorbing element and a portion of said base formed with a cavity connecting the compressor and the lubricant separator and forming a reservoir for said lubricant.
2. In a refrigerating machine, a compressor, a motor therefor, a lubricant separator, and a condenser, together with a base upon which said elements are separately mounted independently of each other, a part of said 45 base being formed into a lubricant reservoir communicating with the lubricant separator and with the compressor respectively.

3. In a refrigerating machine, a compressor, a housing therefor, a motor for said compressor, a lubricant separator, and a condenser, together with a base upon which said elements are separately mounted independently of each other, a part of said base being formed into a lubricant reservoir communicating with the lubricant separator and with the compressor housing respectively, and forming a part of the high pressure side 55 of the refrigerating system, between the compressor and the condenser.

4. In a refrigerating machine the combination with a rotary compressor, a housing therefor, a motor for driving the compressor, a lubricant separator, a condenser, an evaporator, and connections between said compressor and condenser, separator and evaporator, of hollow mounting means for supporting said compressor and separator and communicating therewith, said hollow mounting means also constituting a lubricant reservoir and a base upon which the 70 motor, compressor mounting means and condenser are mounted so as to be movable as one unit.

5. In a refrigerating machine, the combination of a compressor, a housing therefor, a hollow member upon which said compressor is mounted and into which said compressor discharges downwardly, a body of lubricant in said hollow member, an oil pipe extending from said compression into the 80 body of lubricant, a gas passage above the body of lubricant, a lubricant separator communicating with said hollow member and through which the gas and entrained oil pass, said lubricant separator extending parallel with the discharge for said compressor and at least partially in the same horizontal plane, a condenser and an evaporator, and connections between said hollow member, condenser, evaporator and compressor.

In testimony whereof I hereunto affix my signature.

JOHN ALFRED GRIER.
